ELECTRIC FUEL PUMP

Edmond F. Webb, Royal Oak, Mich., assignor to
 Chrysler Corporation, Detroit, Mich., a corpora-
 tion of Delaware

Application October 28, 1933, Serial No. 695,646
 Renewed July 3, 1936

5 Claims. (Cl. 123—139)

This invention relates to an improved fuel pumping system for internal combustion engines and particularly to an electrically energized device of this character.

The main objects of the invention are to provide an electric fuel pumping system for feeding fuels under pressure from a fuel tank to the carburetor or other fuel delivery means of an internal combustion engine; to provide a magnetically operable pump unit in a system of this kind having a solenoid circuit which extends into the fuel tank; to provide a circuit of this kind which has completely closed portions extending into the fuel tank and located in the vicinity thereof, said completely closed portions being absolutely devoid of make and break devices and other spark forming element; to provide a pump unit which may be safely located in the fuel tank where it is free from vapor lock which occurs when the fuel pump is mounted in close proximity to an engine and subjected to the heat radiated therefrom, without the hazard of ignition of fuel or fuel vapor in or around the tank; and to provide a device at a remote location from the fuel tank for intermittently energizing the solenoid of the pump unit.

Other objects of the invention are to provide an improved device for intermittently energizing the solenoid of an electric fuel pumping unit; to provide a device of this character which may be constructed and arranged to be operated by any conventionally located rotative part of an engine, such as the crank shaft, the cam shaft or distributor shaft thereof; to provide a commutator which is adapted to cause the fuel displacing element of the pump unit to perform more strokes per revolution of the commutator rotor at cranking speed of the engine than during idling operation thereof, and substantially fewer strokes per revolution of the commutator rotor during operation of the engine at normal running speeds; and to provide a device of this character which will deliver a greater quantity of fuel per revolution of an engine crank shaft during engine cranking operations than during normal running operations.

An illustrative embodiment of the invention is shown in the accompanying drawing, wherein:

Fig. 1 is a diagrammatic end elevational view of an engine, and a side elevational view of a fuel tank equipped with my improved electric fuel pumping system.

Fig. 2 is an enlarged transverse section of the fuel pumping unit taken on the line II—II of Fig. 1.

Fig. 3 is a transverse sectional view taken on the line III—III of Fig. 1, and illustrating somewhat diagrammatically the commutator stator and rotor of the improved fuel pumping system.

Fig. 4 is a transverse sectional view of the pumping unit taken on the line IV—IV of Fig. 2.

In the form shown, the improved fuel supplying system includes a pumping unit 10 which is disposed in a fuel tank 11 of the type conventionally provided on motor vehicles, and located 10 at the rear end thereof. The pumping unit includes a tubular member 12 which is provided at its upper end with a frusto-conical portion 13 having a radial flange 14 disposed between gaskets 15 mounted on the top surface of the fuel tank 11 and surrounding an opening 16 in the latter. The lower end of the tubular member 12 is also provided with a frusto-conical portion 17 having a radial flange 18 to which a cylindrical casing 20 is attached by bolts 21. The casing 20 includes a lower cup shaped element 22 having a disc 23 disposed over its open extremity, the disc 23 and cup shaped section 22 being secured together by the bolts 21. A gasket 24 is provided between the radial flange 18 of the tubular member 12 and the disc 23 and a gasket 25 is disposed between the latter disc and the cup shaped section 22 of the casing 20 for forming liquid tight seals between the convenient parts of the structure. A valve housing 26 having an inlet opening 27 is secured to the lower extremity of the cylindrical casing 20 by the bolts 21.

Concentrically located in the cylindrical casing 20 is a cylinder comprising a metal sleeve 28 having an opening 29 in its upper extremity surrounded by an inwardly extending flange 30. The lower end of the cylinder 28 is provided with an opening 31 which communicates with the inlet opening 27 of the valve housing 26 through a plurality of passages 32 formed in the lower wall 40 of the cup shaped section 22 of the casing 20. The inlet opening 27 of the valve housing 26 is normally closed by a disc valve 33 which is yieldably held upon its seat by a coil spring 34 bearing between the disc valve and the lower extremity 45 of the cup shaped section 22 of the casing 20.

Reciprocably mounted in the cylinder 28 is a piston 35 which preferably comprises iron or other magnetically attractive metal. The piston 35 has a substantially hollow interior and it is provided with a head portion 36 having outlet apertures 37. The outlet apertures 37 communicate with the interior of the piston and with an inlet opening 38 to the interior of the piston which is normally closed by a disc valve 39. The 55

disc valve 39 is yieldably held upon its seat by a spring 40 bearing between the valve and the internal side of the head 36 of the piston.

A spring 41 normally urges and yieldably holds the piston 35 at the upper end of the cylinder 28, and a solenoid 42 surrounding the cylinder 28 and located between the latter and the peripheral wall of the casing 20 is provided for intermittently urging the piston 35 downwardly against the action of the spring 41. Each upward stroke of the piston 35 opens the valve 33 and draws fuel into the interior of the cylinder 28, and each downward stroke of the piston forces the fuel trapped between the latter and the valve 33 upwardly through the opening 38 past the valve 39 and through the outlet apertures 37. Fuel is in this manner delivered under pressure to the tubular member 12 from which it is conveyed by a conduit 50 to the fuel reservoir 43 of a carburetor 44 which is included in the fuel mixture supply system 48 of an internal combustion engine 49. The rear end of the conduit 50 is provided with a fitting 51 which is threaded in an opening 52 of a disc shaped cap 53 disposed over the opening 16 in the fuel tank, and normally secured to the latter by bolts 54.

The solenoid 42 is electrically connected in a circuit 55 leading from the solenoid to suitable make and break apparatus by which the solenoid is intermittently energized. The circuit 55 includes a pair of lead wires 56 and 57 which are integrally connected with the winding of the solenoid and permanently secured to terminals 58 and 59 mounted on the cap 53 and electrically insulated therefrom by insulating sleeves 60 and 61. The portion of the circuit 55 which is disposed in the tank and the portions thereof located in the vicinity of the tank are permanently closed. One terminal of a battery 62, or other source of power, is directly connected to the terminal 58 of the pump unit, and the other terminal of the battery is directly connected with the make and break apparatus. The terminal 59 of the pump unit is also connected to the make and break apparatus.

The make and break apparatus illustrated in the drawing includes a commutator having a stator 63 and a rotor 64. The rotor may be driven by any conventionally accessible rotative part of the engine 49, but it is preferably operatively connected with some member of the engine which rotates either in unison with the engine crank shaft or at some speed proportional to the speed of rotation of the engine crank shaft.

One operative connection between the crank shaft of the engine and the rotor 64 of the commutator is illustrated in Fig. 1, wherein the engine crank shaft 65 is provided with a pinion 66 which is connected by a chain 77 with a gear 78 mounted on the engine timing shaft 79. A pinion 80 secured to the timing shaft 79 is meshed with a worm gear 81 carried by the distributor shaft 82 of the engine. The shaft 82 operates the conventional distributor mechanism of the engine ignition system and also operates the rotor 64 of the commutator of the fuel pumping system in timed relation to the crank shaft. The rotor of this commutator may, it is recognized, be driven by any rotative part of the engine. For the purpose of convenience of illustration, and in order to disclose one economical manner for operating the commutator rotor, the latter has been combined with the distributor so that the rotor of the distributor and the rotor of the commutator 75 may be driven by the same shaft.

The rotor 64 of the commutator is provided with a contact element 83 which is adapted to successively engage a plurality of circumferentially arranged contact elements formed on the stator 63. The stator may be provided with any desired number of contact elements which are preferably asymmetrically arranged and of different lengths, the construction and arrangement of the contact elements of the stator being such that at low speed rotation of the rotor 64 the 10 solenoid 42 will be energized throughout a greater number of periods of sufficient duration to cause the piston to perform more strokes per rotation of the rotor than during high speed operation of the latter. In the form shown, this is accomplished by providing the stator with three relatively long contact elements 84 which are located in close proximity to each other, and three comparatively short contact elements 85 which are circumferentially spaced at greater distances 20 apart. The exposed portions of the contact elements are separated from each other by suitable dielectric material. The relative lengths of the contact members and the distances therebetween are preferably predetermined so that, during rotation of the rotor at cranking speeds of the engine, each contact element will cause the solenoid 42 to be energized long enough to permit the piston to be moved to the lower end portion of the cylinder 28 and to thereafter be projected upwardly so as to perform one complete discharge stroke for each contact element of the rotor. The construction and arrangement of the contact elements of the stator is such that at idling speeds 30 of the engine, the three closely adjacent contact 35 elements 84 will produce only one effective stroke of the piston and each contact element 85 will cause the piston to perform one partial stroke respectively. At normal running speeds of the engine, however, only one stroke of the piston is 40 produced during each rotation of the rotor 64, for the periods of energization occurring while the contact 83 of the rotor is in engagement with the short contacts 85 of the stator are of insufficient duration to permit the solenoid to overcome the action of the spring 41 and the inertia 45 of the piston, and, therefore, the piston is not moved from its uppermost position shown in Fig. 2. The duration of the periods of interruption of energization of the solenoid brought about 50 by the dielectric material 86 between the relatively long contacts 84 is insufficient to permit the spring 41 to urge the piston 35 upwardly, as contact between the element 83 of the rotor and successive elements 84 of the stator is broken, 55 and therefore the piston remains in its lowermost position substantially from the time the contact 83 engages the first of the series of three contact elements 84 until the contact element 83 becomes disengaged from the last of said series 60 of contact elements. In operation of the engine at its normal running speed, only one effective pumping stroke of the piston occurs, while during operation of the engine at cranking speeds six substantially full strokes of the piston take 65 place. At idling speeds three substantially full strokes and three partial strokes of the piston occur. In this manner the system is conditioned to supply the required amount of fuel to the carburetor at the diverse speeds at which it is 70 operated.

By locating the pump unit in the fuel tank which is conventionally disposed remote from the engine and engine compartment of a vehicle, vapor locking of the pump unit is effectively 75

guarded against. This can be accomplished with the improved vehicle pumping system without the accompanying hazard of fire or explosion resulting from ignition of the fuel or fuel vapor in or around the tank, for all portions of the solenoid circuit located in the tank and all those portions thereof located in the vicinity of the tank are permanently closed. The make and break apparatus is safely located in the engine compartment of the vehicle at a considerable distance from the fuel tank so that there is no danger of ignition of the fuel by the sparks or arcs which may occur during engagement and disengagement of the contacts of the rotor with the contacts of the stator of the commutator.

Although but one specific embodiment of the invention is herein shown and described, it will be understood that various changes in the size, shape, and arrangement of parts may be made without departing from the spirit of my invention, and it is not my intention to limit its scope other than by the terms of the appended claims.

What I claim is:

1. In a vehicle having an internal combustion engine provided with a fuel system including fuel feeding means adjacent said engine and a fuel supply tank remote therefrom; apparatus for supplying fuel under pressure from said fuel tank to said fuel feeding means including a pump unit in said fuel tank having a magnetically operable fuel displacing element and an electro-magnetic member for operating said element, a commutator remote from said fuel tank having a stator member and having a rotor member operatively connected with a rotative part of said engine, one of said members having a plurality of contact elements for engaging the other member, some of said contact elements being of different lengths and asymmetrically arranged to cause said fuel displacing element to perform one effective stroke per contact element during each revolution of said rotor member at cranking speeds of said engine and to cause said fuel displacing element to perform less than one effective stroke per contact element during each revolution of said rotor member at normal running speeds of said engine, and a circuit including a source of electric power and connecting said electro-magnetic member and said contact elements, all portions of said circuit within said fuel tank and in the vicinity thereof being permanently closed.

2. In a vehicle having an internal combustion engine provided with a fuel system including fuel feeding means adjacent said engine and a fuel supply tank remote therefrom; apparatus for supplying fuel under pressure from said fuel tank to said fuel feeding means including a pump unit in said fuel tank having a magnetically operable fuel displacing element and a solenoid for operating said element, a commutator having a stator member and having a rotor member operatively connected with a rotative part of said engine, one of said members having a plurality of contact elements for engaging the other member, some of said contact elements being of different lengths and asymmetrically arranged to cause

said fuel displacing element to perform one substantially full stroke per contact element during each revolution of said rotor member at cranking speeds of said engine and less than one full stroke per contact element during each revolution of said rotor member at idling speeds of said engine and only one effective stroke per contact element during each revolution of said rotor at normal running speeds of said engine, and a circuit including a source of electric power and connecting said solenoid and said contact elements.

3. In an internal combustion engine; a pumping apparatus including a receptacle, a magnetically operable fluid displacing element in said receptacle, resilient means for normally urging said element in one direction, a solenoid for moving said element in an opposite direction against the action of said means, and a commutator including a stator member and a rotor member, means for driving said rotor member in timed relation with said engine, one of said members having a set of widely spaced comparatively short contact elements and a second set of relatively longer contact elements disposed in close proximity to each other, said contact elements being constructed and arranged to cause said fluid displacing element to perform one stroke per contact element during each rotation of said stator at a speed within a predetermined range and to cause said fluid displacing element to perform less than one stroke per contact element during each rotation of said rotor at speeds above said predetermined range.

4. In an internal combustion engine; a pumping apparatus including a receptacle, a magnetically operable fuel displacing element in said receptacle, means for operating said element including an electro-magnetic member, means for driving said rotor member in timed relation with said engine, a commutator including a stator member and a rotor member, one of said members having a set of widely spaced comparatively short contact elements and a second set of relatively longer contact elements disposed in close proximity to each other, said contact elements being so constructed and arranged as to establish a higher ratio of strokes per contact element at low speed operation of said rotor member than at operation thereof at normal running speeds.

5. In an internal combustion engine, a pumping apparatus including a receptacle, a magnetically operable fuel displacing element in said receptacle, means for operating said element including an electro-magnetic member, a commutator including a stator member and a rotor member, means for driving said rotor member in timed relation with said engine, one of said members having contact elements thereon and some of said contact elements being of different effective lengths and being asymmetrically arranged so as to establish a higher ratio of strokes of said fuel displacing element per contact element during low speed operation of said rotor member than during operation thereof at normal running speeds.
